Primary Examiner — Darcey E Gottschalk*Assistant Examiner* — Haley K Schnebele(74) *Attorney, Agent, or Firm* — Birch, Stewart, Kolasch & Birch, LLP(57) **CLAIM**

The ornamental design for a bottom of a bag as shown and described.

DESCRIPTION

FIG. 1 is a perspective view of a bottom of a bag;

FIG. 2 is a front view thereof;

FIG. 3 is a rear view thereof;

FIG. 4 is a bottom view thereof;

FIG. 5 is a top view thereof;

FIG. 6 is a right side view thereof;

FIG. 7 is a left side view thereof; and,

FIG. 8 is an isometric view thereof.

The portions shown in broken lines depict the environment of the bottom of a bag and form no part of the claimed design.

1 Claim, 4 Drawing Sheets(56)
